UNITED STATES PATENT OFFICE.

HENRY DOHERTY AND JOSEPH WADSWORTH, OF PATERSON, N. J.

DESIGN FOR A HANDKERCHIEF.

SPECIFICATION forming part of Design No. 12,873, dated April 11, 1882.

Application filed March 11, 1882. Term of patent 3½ years.

To all whom it may concern:

Be it known that we, HENRY DOHERTY and JOSEPH WADSWORTH, citizens of the United States, residing at Paterson, Passaic county, State of New Jersey, have invented and produced a new and original Design for Handkerchiefs, of which the following is a specification, reference being had to the accompanying drawing, forming a part thereof, in which—

10 A represents the body or surface of the handkerchief, having formed near its four corners a figure, B, which I will proceed to describe. That part of the figure nearest the corner of the handkerchief represents two stems, *a a*, that were cut from the trunk of a tree on which they grew. On the stems there appear three open leaves, *b*. From the under ends of the leaves mentioned projects a sprig, *c*. Higher up on the stems *a a* there appears a flower with its

15

crown *f* in full view, and its unfolded petals *d* surround the same, while on the stems, under the petals, there appear leaves *e*, that are not fully opened, and the whole, *a*, *b*, *c*, *d*, *e*, and *f*, forming sunflowers with stems and leaves cut from the stalk on which they grew.

20 The color of the handkerchief is immaterial, and may be made of any suitable color.

Having described our new and original design, what we claim, and desire to secure by Letters Patent, is—

25 The design for handkerchiefs, having a body, A, and sunflowers B formed in each corner of the same, as shown and set forth.

HENRY DOHERTY.

JOSEPH WADSWORTH.
